BELT CLASP

Carl E. Anderson, East Orange, N. J., assignor to
Eastern Tool & Mfg. Co., Bloomfield, N. J.

Application October 18, 1941, Serial No. 415,520

2 Claims. (Cl. 24—228)

This invention relates to a clasp for belts and the like and is designed to provide a clasp that can be quickly and easily fastened in closed position and easily opened. The clasp is held against accidental opening under lessened tension by the necessity of swinging one of the members a considerable distance out of alignment with the other. The members of the clasp are assembled by first moving them into engagement at an angle to each other and then swinging one or both members until they are substantially in alignment.

The invention is illustrated in the accompanying drawing in which Figure 1 is a face view of a clasp embodying the present invention. Figure 2 is a section on line 2—2 and also showing, in dotted lines, the position of one member to the other when the members are assembled or separated.

The members are preferably made of wire which is of advantage because there is the desired degree of resiliency for smooth connection of the parts.

One member is constructed to provide a space for securing it to a strap or belt. The form shown comprises a wire bent to form a frame consisting of top and bottom strands 10 and 11 and end strands 12 and 13 and an off-set portion formed by the ends 14 of the wire. A clip 15 are continued in inclined convergent strands 16 and 17, end strands 18 and 19 and then into an open loop 20 which is bulged and has the reduced open end 21. This construction forms seals 22 for the hooks of the second member.

The second member is in the form of a loop 23, preferably a closed loop for stiffness. The loop, at its widest part, is of a size to pass readily over the open loop 20. The top and bottom strands 24 define the widest part and converge as at 25 and 26 and then curve outwardly as at 27 and then inwardly and bent to form hooks 28. The hooks 28 are connected by a cross strand or bar 29. The second member is secured to a strap or belt fastened around the end bar 30 formed from the ends of the wire.

The clasp is assembled by placing the second member 23 transversely inside the frame of the first member as shown in dotted outline in Figure 2. The second member is passed over the

loop 20 and then swung to substantial alignment with the first member as shown in full lines.

When the second member is swung the opposed faces of the outwardly turned ends 27 exercise a cam action on the seats 22 at the end of the open loop. This slightly spreads the parts 27 and slightly compresses the sides of the loop 20 and the hooks 28 snap into place in the seats 22. The bar 29 limits the swinging movement of the member 23. The members are now securely clamped together and when they are to be separated the member 23 is swung with pressure enough to cause the cams or parts 27 to ride over the seats 22 and then the member 23 is passed over the loop 20 and then out of the frame of the first member.

I claim:

1. A clasp for belts and the like comprising a member formed of wire and including a part for attachment to a belt and having projecting converging strands which are continued in an inwardly extending open loop with a restricted outer end, and a second member formed into a loop of a size to pass over the open loop and having one end bent back into two hooks connected at their ends by a cross strand, the hooks being inwardly curved on their opposed faces whereby the outer end of the open loop is pressed inwardly by the hooks when the members are swung into alignment and the hooks serve to yieldingly resist movement of the second member toward opening the clasp.

2. A clasp comprising a member having on one end a part for receiving the end of a belt and on the other end formed into a resilient converging wire portion continuing in a bulged inwardly extending open loop, and a second member comprising a loop of a size to pass over the open loop of the first member when the members are substantially at right angles to each other, the loop of the second member having inwardly inclined strands which are curved outwardly at the ends, their opposed faces being spaced apart at a distance slightly smaller than the narrow part of the open loop, the curved part extending into hooks which extend inwardly and are adapted to hook over the narrow part of the open loop, and a cross bar connecting the hook and acting as a stop to limit the movement of the second member.

CARL E. ANDERSON.
